BEAM HANGER

Stephen Bullum, Overton, Tex., assignor of three-fourths to A. D. Gaston, Austin, Tex., and one-fourth to Bullum, Incorporated, Austin, Tex.

Application November 18, 1933, Serial No. 698,641

13 Claims. (Cl. 74—103)

This invention relates to new and useful improvements in beam hangers.

One object of the invention is to provide an improved beam hanger for suspending from the walking beam the polish rod of a well pumping rig, whereby a straight lift is provided for the rod and certain other advantages are obtained.

A particular object of the invention is to provide a beam hanger which may be adjusted with a stick from the floor of the derrick, thus obviating the necessity of climbing upon the beam or the use of tools.

A further object of the invention is to provide a beam hanger in which the parts are held in positive relation to each other and also in which any tendency to twist or buckle is obviated.

Still another object of the invention is to provide a beam hanger which will lend itself to ready adaptation for either a stirrup or T-hanger type of mounting.

A construction designed to carry out the invention will be hereinafter described, together with other features of the invention.

The invention will be more readily understood from a reading of the following specification and by reference to the accompanying drawings in which an example of the invention is shown, and wherein:

Figure 1 is a side elevation of a walking beam and pumping rig, wherein the polish rod is suspended by a hanger constructed in accordance with the invention and of the T-hanger type.

Figure 2 is an enlarged elevation of the hanger in position when the beam is at the lower end of its swing.

Figure 3 is a similar view with the beam at the upper end of its swing.

Figure 4 is a front elevation of the hanger and beam.

Figure 5 is a detail of the hanger, partly in section and partly in elevation.

Figure 6 is a perspective view of the T-hanger.

Figure 7 is a perspective view of the head.

Figure 8 is a perspective view of the stop bar.

Figure 9 is a perspective view of the dog for engaging the ratchet teeth of the stop bar.

Figure 10 is a front elevation of the hanger and beam having a stirrup hanger; and

Figure 11 is a perspective view of the stirrup hanger.

In the drawings numerals and letters are both employed to designate elements shown in the drawings, letters being employed for parts in common use and numerals being employed to

point out the structure in which the invention is embodied.

An ordinary walking beam A is hinged upon a Samson post B. The polish rod C is illustrated as extending from the stuffing box D of the casing head. The walking beam is operated in the usual manner, which it is not believed necessary to describe.

In Figures 1 to 6 inclusive, the numeral 10 designates a T-hanger. This hanger has a transverse rocker bar 11 across its top adapted to engage in the usual notches E on top of the beam and upon each side of the slot F in the end of said beam. The shank of the hanger extends down through this slot and is free to swing therein. At the lower end of the hanger 10 and a substantial distance below the beam, a clevis 12 is provided. This clevis is made integral with the hanger, extends rearwardly and has a pair of opposite apertures 13 and a pair of opposite apertures 14, as is best shown in Figure 6. The apertures 13 underlie the shank of the hanger, while the apertures 14 are offset rearwardly therefrom.

A sector-shaped head 15 is provided with an aperture 16 for receiving a pin 17, which engages in the apertures 14 for pivotally supporting the upper outer extremity of the head in the clevis. The pin 17 may be suitably fastened. The head is preferably of skeleton formation and includes a curved or segmental front rocker 18, a top bar 19, and a bottom bar 20, the aperture 16 being located substantially at the intersection of the top bar and the rocker.

A rocker link 21 is hinged upon a pin 22 mounted in the aperture 13 of the clevis 12, whereby said link is suspended from the clevis and overlies the upper portion of the rocker 18. The lower end of the link 21 is pivoted at 23 to the upper end of an inverted T-hanger 24. The rocker is provided with a recess 25 for receiving the joint 23 and permitting the link 21 and inverted T-hanger 24 to lie upon the face of the rocker when it is swung to its upper position, as is shown in Figure 3. Hanger rods 27 are pivoted on the lower end of the inverted T-hanger and these rods support a clamp 28 and are disposed on each side of the polish rod C, which has its upper end fastened in said clamp.

It will be observed that when the walking beam A is in its central or intermediate position, as is shown in Figure 1, the pivots of the link 21 and T-hanger 24 and all of the parts therebelow are vertically aligned. When the beam is swung downwardly from this position to the position

shown in Figure 2, this alinement is maintained. When the beam is swung to its upper position, the hanger rods 27 are still maintained in vertical alinement with the polish rod. In view of the foregoing, the polish rod is maintained in vertical alinement throughout the entire stroke or swing of the beam.

One of the important features of the invention resides in the means for controlling the swinging 10 of the head 15 and for holding it in proper position to support the link and inverted T-hanger when necessary. Co-extensively with the bottom bar 20 is a slideable stop bar 29. This bar extends through a guide loop 30 at the top of the 15 bar 20 and a second guide loop 31 near the upper end of said bar. The bar 29 is mounted to slide along the underside of the bar 20 and is provided with ratchet teeth 32 along its bottom side. A yoke-shaped dog 33 straddles the two bars and is 20 pivoted to an ear 34 (Figure 7) so as to hang from the head and to engage the ratchet teeth 32, as is best shown in Figure 5.

The tendency of the stop bar 29 is to slide downwardly thus causing the teeth of its rack 32 25 to swing the dog 33 downwardly and thus support said bar. By swinging the dog upwardly, the bar 29 can be slid upwardly until the dog rides out of engagement with the ratchet teeth, as is shown in dotted lines in Figure 5. When this 30 occurs, the stop bar will be released and will be free to slide downwardly along the bottom bar 20. It is obvious that a workman standing on the floor of the derrick may reach the dog with a stick or pole and swing the same upwardly to 35 release the stop bar without climbing onto the beam. If he wishes to elevate the stop bar, he merely has to place his stick against the lower end of said bar and push it upwardly. The ratchet teeth will pass through the dog when this 40 is done.

The stop bar 29 is provided at its upper end with a flat cap 35. A strike pad 36 made of rubber belting or any other suitable material is fastened on the under side of the beam A so as 45 to be engaged by the cap 35 to cushion the swing of the head 15 and also to protect the beam against wear. It will be observed that when the beam swings downwardly from its position shown in Figure 1 to its position shown in Figure 2, the link 21 and the inverted T-hanger 24 will tend to 50 swing the hanger 10 to a vertical position, where by the head 15, owing to its offset pivot 17, will be so swung as to carry the rocker 18 away from said links, thereby not interfering with the vertical alinement of the links and the parts therebelow.

As the beam swings upwardly, the vertical alinement is maintained, but the cap 35 approaches the pad 36 owing to the decreasing of 60 the angle between the shank of the hanger 10 and the underside of the beam. When the beam reaches the intermediate portion of its swing the cap will engage the pad and prevent further swinging of the hanger and head. This will 65 cause the rocker 18 to be swung into contact, first with the link 21 and finally with the inverted T-hanger 24. As the swing progresses from the intermediate position upwardly, the 70 pivot point successively changes from the pin 22 to the joint 23 and finally to that of the hanger bars 27. Thus, it will be seen that during the entire upward swing, the pivot point of the hanger bars 27 travels in a direct vertical path. 75 Since these rods support the polish rod, it is

obvious that a straight lift of said rod is had during the entire operation.

In Figures 10 and 11, I have shown another form of the invention which is adapted to be used in connection with a walking beam A, the end of which is not provided with a slot F. With this type of beam there is no way of supporting the T-hanger 10, so I provide in place of said hanger a stirrup 10' which engages over the end of the beam A (Figure 10). The stirrup has a 10 clevis 12', similar to the clevis 12, at its lower end. This clevis is preferably made integral with the stirrup, extends rearwardly, and has a pair of opposite apertures 13' and a pair of opposite apertures 14', as is best shown in Figure 11. The 15 apertures 13' underlie the stirrup, while the apertures 14' are rearwardly therefrom. The apertures 13' have the upper end of the link 21 pivoted therein on the pin 22 and the pin 17 pivotally supports the sector-shaped head 15 in 20 the apertures 14'. The remaining parts are identical with the form shown in Figures 1 to 9, and since the operation of both forms is the same, an explanation is deemed unnecessary.

The description which has been given recites 25 more or less detail of a particular embodiment of the invention, which is set forth as new and useful, however, I desire it understood that the invention is not limited to such exact details of construction, because it is manifest that changes 300 and modifications may be made, within the scope of the appended claims, without departing from the spirit of the invention.

What I claim and desire to secure by Letters Patent, is:

1. A beam hanger for walking beams comprising, a head, means for pivotally supporting said head from a walking beam, articulated means for suspending a polish rod below the head, a movable stop bar extending from the head for 400 engaging the beam, and a ratchet adjustment for said bar for permitting the bar to be slid with respect to said head.

2. A beam hanger for walking beams comprising, a head, means for pivotally supporting said head from a walking beam, articulated means for suspending a polish rod below the head, a stop bar slidably supported by the head and projecting from the head for engaging the beam, a ratchet on the bar, and a dog carried by the 500 head and engaging the ratchet.

3. A beam hanger for walking beams comprising, a hanger for pivotally mounting on a walking beam and depending therefrom, a head pivoted to the hanger, an articulated suspensory 550 hinged to the hanger and engaging the head, means for attaching the suspensory to the polish rod of a well pump, a stop carried by the head and having a free end for engaging the beam during the upper part of the stroke to limit the 600 swing of the head upon the swing of the beam, and for positioning said head for supporting the suspensory, and means for adjusting said stop arranged to be adjusted from the floor of the 650 derrick.

4. A beam hanger for walking beams comprising, a hanger for pivotally mounting on a walking beam and depending therefrom, a sector-shaped head pivoted to the hanger and having a curved rocker, an articulated suspensory 700 pivoted to the hanger and overlying the rocker of the head, means for securing a polish rod to the suspensory, a movable stop bar extending from the head and having a free end for engaging the beam during the upper part of 750

- the stroke, and means for adjusting the bar with respect to said head.
5. A beam hanger for walking beams comprising, a hanger for pivotally mounting on a walking beam, a sector-shaped head pivoted to the hanger and having a curved rocker, an articulated suspensory pivoted to the hanger and overlying the rocker of the head, means for securing a polish rod to the suspensory, a movable stop bar extending from the head for engaging the beam, and a ratchet adjustment for said bar for permitting the bar to be slid with respect to said head. 5
6. A beam hanger for walking beams comprising, a hanger for pivotally mounting on a walking beam, a sector-shaped head pivoted to the hanger and having a curved rocker, an articulated suspensory pivoted to the hanger and overlying the rocker of the head, means for securing a polish rod to the suspensory, a stop bar slidably supported by the head and projecting from the head for engaging the beam, a ratchet on the bar, and a dog carried by the head and engaging the ratchet. 10
- 20 7. A beam hanger for walking beams comprising, a T-hanger for pivotally mounting on a walking beam and depending therefrom, a sector-shaped head pivoted to the lower end of the T-hanger and having a curved rocker, a link also pivoted to the lower end of the T-hanger and overlying the upper portion of the rocker of the head, an inverted T-hanger pivoted to the link and overlying the lower portion of the rocker of the head, means for securing a polish rod to the lower end of the inverted T-hanger, and a stop slidably mounted on the head and having a free end and extending therefrom for engaging the beam during the upper part of the stroke. 25
- 30 8. A beam hanger for walking beams comprising, a T-hanger for pivotally mounting on a walking beam, a sector-shaped head pivoted to the lower end of the T-hanger and having a curved rocker, a link also pivoted to the lower end of the T-hanger and overlying the upper portion of the rocker of the head, an inverted T-hanger pivoted to the link and overlying the lower portion of the rocker of the head, means for securing a polish rod to the lower end of the inverted T-hanger, a movable stop bar extending from the head for engaging the beam and a ratchet adjustment for said bar for permitting the bar to be slid with respect to the head, said bar being adjustable from the floor of the derrick. 35
- 35 9. A beam hanger for walking beams comprising, a T-hanger for pivotally mounting on a walking beam and depending therefrom, a sector-shaped head pivoted to the T-hanger and having a curved rocker, an articulated suspensory pivoted to the T-hanger and overlying the rocker of the head, means for securing a polish rod to the suspensory, a movable stop bar extending from the head for engaging the beam during the upper part of the stroke to limit the swing of the head upon the up-swing of the beam and for positioning said head for supporting the suspensory, and means for adjusting said stop arranged to be adjusted from the floor of the derrick. 40
- 40 10. A beam hanger for walking beams comprising, a stirrup for pivotally mounting on and depending from a walking beam, a head pivoted to the stirrup an articulated suspensory hinged to the stirrup and engaging the head, means for attaching the suspensory to the polish rod of a well pump, a stop carried by the head and having a free end for engaging the beam during the upper part of the stroke to limit the swing of the head upon the up-swing of the beam and for positioning said head for supporting the suspensory, and means for adjusting said stop arranged to be adjusted from the floor of the derrick. 45
- 45 11. A beam hanger for walking beams comprising, a stirrup for pivotally mounting on and depending from a walking beam, a sector-shaped head pivoted to the lower end of the stirrup and having a curved rocker, a link also pivoted to the lower end of the stirrup and overlying the upper portion of the rocker of the head, an inverted T-hanger pivoted to the link and overlying the lower portion of the rocker of the head, means for securing a polish rod to the lower end of the inverted T-hanger, and a stop slidably mounted on the head and having a free end extending therefrom for engaging the beam during the upper part of the stroke. 50
- 50 12. A beam hanger for walking beams including a hanger pivotally mounted on and depending from a walking beam, a sector shaped head at the lower end of said hanger and having a curved rocker extending downwardly therefrom, a stop bar extending from said head and having a free end for engaging said beam during the upper portion of its stroke, an articulated suspensory connected with said hanger overlying said curved rocker of the head, and means for securing a polish rod to said suspensory. 55
- 55 13. A beam hanger for walking beams including a hanger pivotally mounted on and depending from a walking beam, a sector shaped head at the lower end of said hanger and having a curved rocker extending downwardly therefrom, a stop bar extending from said head and having a free end for engaging said beam during the upper portion of its stroke, means for adjusting said stop bar longitudinally from said head so as to change the point of the stroke where it engages the beam, an articulated suspensory connected with said hanger overlying said curved rocker of the head, and means for securing a polish rod to said suspensory. 60

STEPHEN BULLUM.
